CLAIM

The ornamental design for a housing for an outdoor coil of an air conditioning system, as shown.

DESCRIPTION

FIG. 1 is a top plan view of a housing for an outdoor coil of an air conditioning system, showing our new design;

FIG. 2 is a front elevation view thereof;

FIG. 3 is a right side elevation view thereof;

FIG. 4 is a rear elevation view thereof;

FIG. 5 is a left side elevation view thereof; and

FIG. 6 is an enlarged fragmentary plan view of a portion of the top thereof.
